(57) **CLAIM**

The ornamental design for a scented fragrance warmer, as shown and described.

DESCRIPTION

FIG. 1 is a perspective view of a scented fragrance warmer, showing my new design;

FIG. 2 is a front view of the scented fragrance warmer shown in FIG. 1;

FIG. 3 is a rear view of the scented fragrance warmer shown in FIG. 1;

FIG. 4 is a first side view of the scented fragrance warmer shown in FIG. 1;

FIG. 5 is a second side view of the scented fragrance warmer shown in FIG. 1;

FIG. 6 is a top view of the scented fragrance warmer shown in FIG. 1; and,

FIG. 7 is a bottom view of the scented fragrance warmer shown in FIG. 1.

The uneven broken line immediately adjacent to the shaded area represents the bounds of the claimed design. All other uneven broken lines represent the remaining portion of the scented fragrance warmer. The uneven broken line representations in FIGS. 1-7 are for illustrative purposes only and form no part of the claimed design.
